UNITED STATES PATENT OFFICE.

WILLIAM A. HANVEY, OF BIG RAPIDS, MICHIGAN, ASSIGNOR OF ONE-HALF
TO WILLIAM LAMBERT, OF REED CITY, MICHIGAN.

RAIL-JOINT.

No. 848,901.

Specification of Letters Patent.

Patented April 2, 1907.

Application filed December 18, 1906. Serial No. 347,731.

To all whom it may concern:

Be it known that I, WILLIAM A. HANVEY, a citizen of the United States, residing at Big Rapids, in the county of Mecosta and State of Michigan, have invented a new and useful Rail-Joint, of which the following is a specification.

This invention has relation to rail-joints; and it consists in the novel construction and arrangement of its parts, as hereinafter shown and described.

The object of the invention is to provide means for connecting the ends of rails together and support the several parts of the rails in order to reduce the tendency of the rails to wear at their ends, with the consequent injury to the rolling-stock. The joint consists primarily in providing the sides of the vertical web of the rails with laterally-extending shoulders. Side plates are provided with recesses for the reception of said shoulders and have upper and lower edges of such configuration as to fit snugly against the heads and flanges of the rails, and thereby brace the ends of the rail and hold the same in proper alinement. The outer surfaces of the said plates are provided with shoulders which serve to retain the securing-bolts against rotation and also afford means for retaining nut-locking devices, as will be hereinafter explained.

In the drawing the figure is a transverse sectional view of the rail-joint.

The vertical web 1 of the rails is provided with the laterally-extending shoulders 2, the upper and lower edges of which are inclined or beveled, as at 3. The plates 4 are provided upon their inner faces with the recesses 5, which receive the shoulders 2. Said recesses 5 fit snugly about the said shoul-

ders. The upper and lower edges of the plate 4 are beveled in order to fit snugly against the heads and flanges of the rails. The outer sides of the plate 4 are provided with shoulders 6, which serve as stops 45 against which the heads of the bolts 7 may bear, and which are thus retained against rotation. The said shoulders 6 may also serve as a stop for a nut-locking plate 8 and may retain the same against rotation. The 50 edge of the said plate 8 opposite to that which engages the shoulder 6 is bent down against the side of the nut 9, and thus nut-locking means is provided at the joint. By reason of the fact that the plates 4 fit snugly 55 against the sides and between the heads and flanges of the rails a substantial joint is provided, and one rail is braced against the other and the tendency to sag or wear at the joint is reduced to a minimum. Consequently 60 the rolling stock is not subjected to unnecessary wear.

Having described my invention, what I claim as new, and desire to secure by Letters Patent, is

In combination with rails having upon their webs laterally-extending shoulders, the upper and lower edges of which diverge from each other toward the outer faces of the shoulders, plates having recesses which receive said shoulders and fit snugly about the same and bolts passing transversely through the plates and rails.

In testimony that I claim the foregoing as my own I have hereto affixed my signature 75 in the presence of two witnesses.

WM. A. HANVEY.
